COMBINATION BATH SPRAY DEVICE AND TEMPERATURE INDICATOR

William C. Baxter, Rochester, N. Y., assignor to Trimble, Inc., Rochester, N. Y., a corporation of New York

Application February 27, 1951, Serial No. 213,024

2 Claims. (Cl. 73—343)

This invention relates to a combination bath spray device and temperature indicator and has for its purpose to afford a simple and practical structure that is especially adapted for use in connection with the bathing of infants.

A more particular purpose of the invention is to provide an efficient spray head in which the water acts as an injector to draw in air that is thoroughly intermingled with the water before its discharge so as to reduce the pressure of the water and provide a softlike gentle spray offering little shock as it strikes the infant, and which at the same time gives an indication of the temperature of the water at a point just before it emerges from the spray head on to the body of the infant.

A further object of the invention is to provide an economical and simple structure for admitting air to a spray head connected with a flexible water hose of a bath spray, and to arrange a thermometer so as to give an indication of the temperature of the water in the chamber where it is mixed with the incoming air.

Another purpose of the invention is to provide a simple arrangement that enables constructing and readily assembling the parts of a spray head in such fashion that air is drawn in through a passage surrounding the spray head inlet and water hose while a thermometer is positioned in the same passage with its bulb projecting into the mixing chamber of the spray head where the water and air are intermingled just before emerging from the spray head, thus enabling a determination of the temperature of the water at a point immediately before it strikes the body of the infant.

An additional object of the invention is to afford an arrangement of parts whereby the spray head can be readily attached to a flexible water hose and a rigid transparent sleeve surrounding the spray head inlet and hose can be readily attached to the spray head while a perforate spray plate is detachably secured to the head.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in side elevation of a combination bath spray device and temperature indicator constructed in accordance with a preferred embodiment of the invention;

Fig. 2 is a longitudinal sectional view taken

centrally of Fig. 1 on the line 2—2 looking in the direction indicated;

Fig. 3 is an enlarged detail sectional view taken on the line 3—3 of Fig. 2 looking in the direction indicated;

Fig. 4 is an enlarged detail sectional view taken on the line 4—4 of Fig. 2 with the thermometer removed and looking in the direction indicated;

Fig. 5 is a view in end elevation of the spray head;

Fig. 6 is a similar view with the perforate spray plate removed, and

Fig. 7 is a transverse sectional view on line 7—7 of Fig. 2 looking in the direction indicated.

Referring more particularly to the drawings in which like reference numerals refer to the same parts throughout the several views, 1 designates a hollow spray head constructed of transparent medium soft Vinylite or suitable plastic or other material that is resilient and flexible, sufficiently to hold its normal shape and permit detachable connection of the parts with which it is associated.

The hollow spray head 1 affords a mixing chamber 2 between its inner and outer ends and has a preferably curved outer surface, as shown in Figs. 1 and 2, with a wide outer end and a reduced inner end, while 3 designates a transverse wall adjacent to the inner end of the spray head terminating in an elongated neck, the outer end 4 of which is provided with exterior ribs 5 and adapted to receive a water hose 6 which may be of Vinylite or any desirable yieldable material that can be forced over the end or connecting portion 4 of the neck and held thereon by a split metal ring 7. The inner end 4 or connecting portion of the neck is preferably of reduced diameter to afford a shoulder 8 against which the water hose abuts when secured in position.

The elongated neck has extending therethrough a water inlet shaped as shown in Fig. 2 to afford a reduced portion 9 at the center and widening gradually toward both ends, while 11 designates transverse openings in the elongated neck connecting said reduced central portion 9 with the area surrounding the neck to permit air to be drawn in through the openings 11 as water under pressure is forced through the reduced area 9 into the mixing chamber 2. The water acts as an injector to draw in the air which is thoroughly intermingled with the water in the mixing chamber 2 by the turbulent action created as movement of the water is interrupted when it strikes the spray plate at the outlet end of the spray head.

In order to afford a housing for the thermometer tube to be described presently and an air chamber from which air can be continuously drawn into the water inlet, there is provided a rigid transparent sleeve 12 formed of hard Vinylite or other plastic or suitable transparent material, the sleeve 12 having a collar 13 at its inner end which enters a recess in the head and interlocks with an overlying portion or shoulder 14 formed at the inner end of the yieldable spray head. At its opposite end, the sleeve 12 is constructed to fit more or less snugly around the water hose 6, and includes an end wall 15 that has a central opening to receive the water hose 6 and adjacent openings 16 to permit air to enter between the sleeve and the water hose, whence it passes through the sleeve and into the openings 11 which communicate with the water inlet.

The inner end wall 3 of the spray head is provided with an enlargement 17 extending into the mixing chamber 2 and having an opening 18 therethrough to receive the thermometer 19, which projects through the opening 18 in the spray head into the passage afforded between the transparent sleeve 12 and the water hose 6. The transparent sleeve 12 is provided on its exterior with a temperature indicating scale 21, the thermometer being positioned in the spray head so that a fixed indication on the thermometer corresponds with a predetermined mark, "100°" for instance, on the thermometer scale, so that after the thermometer is once arranged in the sleeve, movement of the liquid in the thermometer will give an accurate reading on the scale on the outside of the transparent sleeve 12, the thermometer liquid being visible through the sleeve.

22 designates integral strengthening ribs or flanges projecting radially from the spray head 1 into the mixing chamber 2, while 23 designates a perforate spray plate of metal or other suitable material, its outer edge or periphery entering a groove 24 and held by the overlying flange 25 at the outer end of the spray head 1.

To assemble the parts, the rigid transparent sleeve 12, before being connected to the spray head, is first positioned around water hose 6 and the latter is then forced over the inner end 4 of the neck or hose connector on the spray head and secured by the split metal ring 1. Following this, the outer end of sleeve 12 is forced toward the spray head into the recess between the neck 4 and the surrounding portion of the spray head until flange 13 of the sleeve 12 springs under and interlocks with the shoulder 14 of the spray head, which is sufficiently yieldable to permit such engagement and detachable connection between the spray head and rigid sleeve.

The tube of the thermometer 19 is next inserted through the outer open end of the spray head into the opening in the enlargement 17 and into the space between the sleeve 12 and the water hose 6 until it is properly positioned with reference to the scale 21 on the sleeve 12, the thermometer having a fixed marking thereon corresponding to a predetermined indication on the scale. The thermometer is held frictionally in its adjusted position by the resiliency of the neck 17 of the spray head which engages the tube of the thermometer with sufficient tightness to prevent water from passing from the mixing chamber to the space around the thermometer tube or between the sleeve 12 and the water hose. With the thermometer in this position, the perforate spray plate 23 is inserted into the outer end of the spray head which engages yieldably

over the periphery of the spray plate and the device is ready for operation.

It will be understood that the flexible water hose 6 is connected with any suitable source of water supply such as a conventional faucet and when the water is turned on, it issues through the reduced opening 9 of the water inlet of the spray head with sufficient force to draw air from the surrounding space between the sleeve 12 and the water hose and spray head through openings 11 into the water inlet at its narrowest point. The water and air emerge through the gradually widening passage into the mixing chamber 2, and the water being interrupted in its travel by the spray plate 23 which acts as a baffle, is thrown backwardly in the mixing chamber 2 where there is a turbulent intermingling of the air and water, and the water issues from mixing chamber 2 through the spray plate 23 at considerably reduced pressure owing to the enlarged outer end of the spray head and the amount of air with which the water has become charged. The temperature of the water in the mixing chamber 2 can be instantly determined by observing the thermometer liquid through the transparent sleeve 12 in relation to the scale 21 and thus, at any instant, one can determine the temperature of the water as it strikes the body of the infant, since the temperature is taken within the mixing chamber and gives an accurate reading of the water in its final aerated state just before issuing from the spray head through the perforate spray plate 23.

While the invention has been described with reference to the structural embodiment herein shown, it is not confined to the precise details set forth and this application is intended to cover such modifications or departures as may come within the purposes of the improvement and the scope of the following claims.

I claim:

1. A hollow spray head of yieldable resilient material having a transverse wall adjacent to its inner end terminating in an elongated neck arranged centrally of said wall and having a water inlet opening extending therethrough, the outer end of said neck being connectible to a water hose, a handle comprising a rigid transparent elongated sleeve carried by said head surrounding and spaced from said neck and water hose, said sleeve extending a substantial distance along the water hose and affording between the hose and said sleeve a well of a length and width sufficient to house a thermometer tube, and a spray plate secured at the outer end of the head, said hollow spray head including a chamber between the spray plate and the water inlet opening and said transverse wall having an enlargement projecting into said chamber with a thermometer-receiving opening extending through said enlargement and transverse wall whereby a thermometer may be located with its bulb in said chamber and its tube arranged in said well between said water hose and said elongated sleeve and parallel thereto.

2. A hollow spray head of yieldable resilient material having a transverse wall adjacent to its inner end terminating in an elongated neck arranged centrally of said wall and having a water inlet opening extending therethrough, the outer end of said neck being connectible to a water hose, a handle comprising a rigid transparent elongated sleeve surrounding and spaced from said neck and water hose, said sleeve extending a substantial distance along the water hose and

affording between the hose and said sleeve a well of a length and width sufficient to house a thermometer tube, a collar at the inner end of the sleeve projecting into a recess in the head and having interlocking engagement with a shoulder therein, and a spray plate secured at the outer end of the head, said hollow spray head including a chamber between the spray plate and the water inlet opening and said transverse wall having an enlargement projecting into said chamber with a thermometer-receiving opening extending through said enlargement and transverse wall whereby a thermometer may be located with its bulb in said chamber and its tube arranged in said well between said water hose and sleeve and parallel therewith.
